UNITED STATES PATENT OFFICE

2,258,965

DISCHARGE CONVEYER FOR LOADING MACHINES

George Baechli, Franklin, Pa., assignor to Joy Manufacturing Company, a corporation of Pennsylvania

Application June 4, 1940, Serial No. 338,771

2 Claims. (Cl. 198—121)

This invention relates to mobile loading machine of the type adapted to load coal in underground coal mines into cars or other haulage units for transportation from the coal producing area of the mine to the coal preparation plant, and particularly to improvements in the discharge conveyer for such loading machines whereby the loader may be readily adapted to operate in coal seams of varying thickness and load coal into transporting devices, such as mine cars, over which the conveyer of the loading machine must extend in order to load the same, of varying height and capacity.

It is customary in coal mining operation since, at best, the working conditions are extremely limited, to employ mine cars and the like to transport the coal from the producing area of the mine to the coal preparation plant at the surface, having the greatest load carrying capacity which it is possible to employ in the height of coal seam being worked, and to secure such capacity the mine car is usually of as great a height as will permit it to pass readily when fully loaded under the roof and roof supporting beams of the mine chamber. That is to say, mine cars are not built to any standard dimensions but for the most part are made specially for meeting conditions in each individual mine, and prior to my invention, it was necessary to make a special discharge conveyer section for substantially each loading machine to permit the machine to be worked in a mine with the existing equipment, thus materially increasing the cost of the loading machine to the operator.

The principal object of this invention is to provide a mobile loading machine for use in underground coal mines having a laterally swinging discharge conveyer adapted to be positioned over a mine car during loading which is capable of being readily adjusted to permit mine cars of varying height to be employed behind the loader and loaded thereby.

Another object of this invention is to provide a mobile loading machine having a laterally swinging discharge conveyer adapted to be positioned over a mine car, or other haulage unit, in which the laterally swinging section of the conveyer is articulated for movement in a vertical plane whereby the height of the discharge end of the conveyer may be readily varied to meet the height requirement encountered in different coal mines.

A further object is to provide a sectional discharge conveyer for a mobile loading machine which is sturdy of construction, easy to manu-

facture and install on the machine, and which permits of more universal use of the loader.

These and other objects which will hereinafter be made apparent to those skilled in this particular art, are accomplished by means of this invention, one embodiment of which is described in the following specification and illustrated in the accompanying drawing, wherein:

Fig. 1 is a plan view of a mobile loading machine provided with a sectional discharge conveyer made in accordance with my invention, and mounted for lateral swinging movement relative to the body of the loading machine;

Fig. 2 is a view in side elevation of the loading machine shown in Fig. 1;

Fig. 3 is an enlarged view in elevation of a portion of the discharge conveyer showing the means for varying the height of the discharge end thereof;

Fig. 4 is an enlarged sectional view taken on the line IV—IV of Fig. 3 showing the means for varying the elevation of the discharge end of the conveyer; and

Fig. 5 is an enlarged sectional view taken on line V—V of Fig. 1.

Referring to the drawing in detail 10 represents a mobile loading machine mounted to travel throughout the various mine chambers on self-laying track 11 of the endless chain type. At 30 the forward end of the loading machine, a loading or gathering head 12 is pivoted, at 13, for swinging movement in a vertical plane which has gathering arms 14 thereon for gathering the coal from the mine floor and delivering the same into a conveyer pan 15 forming a part of the gathering head 12. Also pivoted at 13 for vertical swinging movement is a conveyer pan 19 registering with the conveyer pan 15 on the gathering head 12 which terminates at its rear 35 end in a fan section 20 of pre-determined radius. Abutting against the fan section 20 of the conveyer pan 19 is a sectional discharge conveyer 21 which is pivoted to the conveyer pan 19 for lateral swinging movement in the manner set forth and disclosed in Arentzen Patent #1,785,402. The sectional discharge conveyer 21 is swung laterally by means of hydraulically operated double acting jacks 22—22 mounted on the sides of the discharge conveyer in cooperation with cables 23—23 having one end attached to the jacks 22. Each cable 23 passes around a pulley or sheave 24 mounted on the end of the piston rod of the jack 22 and then around a sheave 25 and has its opposite end attached to the edge 50 of the fan section 20 of the conveyer pan 19.

55

The admission of fluid to the jacks is controlled by a suitable valve arranged, when operated, to deliver fluid to the jacks so that one will be expanded and the other contracted, and thus swing the conveyer 21 laterally.

Coal delivered into the conveyer pan 15 is conveyed rearwardly of the machine end by flights 16 on an endless chain 17 of universal construction which passes, at the front end of the loader, around a drive shaft 18 journaled in the gathering head 12 and at its rear end around an idler shaft 18a mounted in the side walls of the discharge conveyer 21.

The means for swinging the gathering head 12 and conveyer pan 19 in vertical planes and the means for driving the gathering arms 14 and operating the conveyer chain 17 are old and well known in the art and form no part of the present invention.

In order to make the use of the loading machine more universal, and to permit it to load mine cars of varying height, the discharge conveyer 21 is made up of two sections pivoted together so that the outer section may be raised and lowered relative to the inner section, to vary the height of the discharge end of the conveyer. The forward or front section 21a of the discharge conveyor 21 which is relatively short in length and terminates at a point substantially midway between the forward and rear end of the hydraulic jacks 22 comprises a lower or bottom deck 27, an upper or top deck 28 which is vertically spaced above the bottom deck and side walls 29 to which the bottom and top decks are united. The rear section 21b of the discharge 30 conveyor 21 is likewise of two deck construction and has a lower deck 30 which is hinged at 31 to the lower deck 27 of the front section 21a, an upper deck 32 having its forward end curved downwardly as at 33 to extend underneath the upper deck 28 of the forward section 21a, and side walls 34 to which the sides of the decks 30-32 are attached. The side walls 34 at their forward ends abut against the rear ends of the side walls 29 on the front section 21a of the discharge conveyer pan.

To raise and lower the discharge end of the rear section of the discharge conveyer pan and vary the angle at which said conveyer extends rearwardly from the machine, a bolt 35 having right and left hand threads on its opposite end, and a wrench flat 36 in the center thereof, is threaded into nuts 37 and 38 journaled in brackets 39-40 secured to the side walls 29-34 respectively and in the side walls of the discharge conveyer sections 21a-21b. From this construction it is apparent that by turning the bolt 35 on each side of the discharge conveyer 21, the rear section 21b thereof can be readily turned about the hinge pin 31 and the height thereof readily varied without varying the height of the front section 21a of the discharge conveyer, and that since the forward end 33 of the top deck plate 32 of the rear section 21b is curved down-

wardly, a continuous floor surface is always maintained between the two sections of discharge conveyer 21 over which coal and other material may be readily conveyed.

It is also apparent that since the forward section 21a of the discharge conveyer 21 terminates substantially intermediate of the hydraulic jacks 22, and since the jacks are located below the brackets 39-40 the sheaves 24-25 will always be protected by the side walls 29-34 of the front and rear sections of the conveyer regardless of the elevation of the rear section 21b since the position of the sheave 25 is fixed with relation to the side wall 29, and the bolt 36 is of such length that lowering of the rear section to such an extent that sheave 24 would extend above the side wall 34 is prevented.

While I have described one embodiment of my invention, it is apparent that certain changes, modifications, substitutions, omissions, and additions may be made therein without departing from the spirit of my invention or the scope of the appended claims.

What I claim as new and desire to secure by Letters Patent is:

1. A discharge conveyer for a mobile loading machine, comprising a front section having an upper deck and a lower deck, a rear section having a lower deck hinged to the lower deck of the front section and an upper deck provided with a downwardly curved forward edge adapted to extend underneath the upper deck of said front section, and means for varying the elevation of said rear section relative to the front section including opposed brackets secured to the front and rear sections of said conveyer on each side thereof, a nut journaled in each of said brackets, and a bolt having right and left hand threads on its opposite ends threaded into the opposed nuts 40 on each side of said conveyer, whereby turning of the bolt in one direction will lower said rear section and turning in the opposite direction will elevate said rear section.

2. A discharge conveyer for a mobile loading machine, comprising a front section having an upper deck and a lower deck, a rear section having a lower deck hinged to the lower deck of the front section, and an upper deck provided with a downwardly curved forward edge adapted to extend beneath the rear edge of the upper deck of said front section, and means for varying the elevation of said rear section relative to said front section including opposed brackets secured to the side walls of the front and rear sections 55 of said conveyer on each side thereof, a nut having trunnions thereon journaled in each of said brackets, and the side wall to which said bracket is attached, and a bolt having right and left hand threads on its opposite ends threaded into their opposed nuts on each side of said conveyer, whereby turning of the bolt in one direction will lower said rear section and turning in the opposite direction will elevate said rear section.

GEORGE BAECHLI.
